UNITED STATES PATENT OFFICE.

GUSTAV B. PETSCHÉ, OF YONKERS, NEW YORK.

ROTARY PUMP.

1,380,017.

Specification of Letters Patent. Patented May 31, 1921.

Application filed October 6, 1920. Serial No. 415,146.

To all whom it may concern:

Be it known that I, GUSTAV B. PETSCHÉ, a citizen of the United States of America, and resident of Yonkers, in the county of 5 Westchester, in the State of New York, have invented a certain new and useful Improvement in Rotary Pumps, of which the following is a true and exact description, reference being had to the accompanying 10 drawings, which form a part thereof.

My invention relates to rotary pumps of the type in which the piston consists of an eccentric ring having an extension which forms a partition between the admission and 15 delivery ports of the cylinder and is articulated to a rotary slide moving in a segmental cylindrical bearing. The object of my invention is primarily to provide such a rotary pump or compressor with a grid slide 20 valve, opening to permit the flow of the compressed gas into the delivery chamber and closed positively and accurately at the end of the delivery cycle of the piston by contact with the piston extension. Further objects 25 of my invention are to provide means for actuating the slide valve so that it will open rapidly and completely at the proper point, and to provide in combination with the devices for regulating the movements of the 30 delivery valve a valve moving with or forming a part of the slide to which the piston is articulated, for closing the admission port during the period when the piston is out of contact with the periphery of the cylinder.

35 The nature of my improvements will be best understood as described in connection with the drawings in which they are illustrated and in which—

Figure 1 is a side elevation of a compressor embodying my invention taken as on the line 1—1 of Fig. 2, and

Fig. 2 is a front view of a twin cylinder compressor partly shown in section on the line 2—2 of Fig. 1.

45 A, A', indicate two cylinders formed in a single casting and provided with face plates A² and A³. B is the cylindrical internal periphery of the cylinder A interrupted as indicated at B', B², to give clearances to 50 the piston extension. C is the segmental cylindrical bearing for the slide having formed in it, as shown, an admission port D in communication with the admission chamber D'. E is a passage leading from the 55 delivery side of the compressor to the receiving chamber E'. F is the driving shaft

of the compressor having secured to it eccentrics as indicated at F' on which are seated the eccentric ring pistons G having the extensions G' articulated at their ends as 60 indicated at T to a rock lever I, I', pivoted at H and having formed or attached to it the slide J and practically forming a part of this slide is the admission valve M, the slide being shown recessed between the portions J and M as indicated at J' and the recessed portion lying in communication with the admission chamber through the port d'. This construction is for the purpose of preventing the building up of pressure on the 70 portion of the slide cut away as indicated at J'. O is a valve bushing inserted in the passage E and having formed in it the grid valve seat indicated at O'. P is a grid valve working on this seat and formed, as 75 shown, with a valve stem P' to which is secured a piston Q and a plunger Q'. P² is an extension of the valve stem through a bushel passage in the wall of the compressor lying in the path traversed by the piston 80 extension G' at the completion of its compressing cycle. R is the cylinder in which the piston Q works, the ends of the cylinder being connected by ports indicated at R' and R² and through an adjustable restricting plug R³. S is a cylinder in which works the plunger Q' and, as shown, this cylinder is connected by a pipe S' with a port S² formed through the wall B on the delivery 85 side of the compressor. 90

In operation the gas to be compressed enters from the chamber D' through the port D and after the piston G has come in contact with the wall of the cylinder at B' is compressed, the pressure gradually building up 95 until the pressure in the cylinder equals that in the receiver chamber E'. The port S² is located at such a point that the pressure building up in the cylinder is transmitted through the pipe S' to the cylinder S and 100 acting against the plunger Q' this pressure will, when the pressures above and below the valve are equal, move it rapidly in a direction to open it, smoothness of motion being insured by the dash pot effect of the cylinder 105 P and piston P'. After the valve is opened the end of the rod P² projects into the cylinder so that, as the piston completes its compression cycle and immediately before it leaves contact with the point B', the extension G' comes in contact with the rod and forces the valve back to the closed position. 110

At this point also the admission valve M closes the port D so that as the piston moves from its point of contact at B² to its point of contact at B' the admission valve is closed and any compressed gas contained in the clearance spaces, while it may flow back into this cylinder of the compressor, cannot escape backward into the admission chamber. It is, of course, obvious that after the piston has passed over the port S² pressure is released in the cylinder S so that there is no pressure on piston S tending to oppose the action of the extension G' closing the valve.

Having now described my invention, what I claim as new and desire to secure by Letters Patent, is:

1. In a rotary compressor having an eccentric ring piston provided with an extension forming a partition between the admission and delivery ports of the compressor cylinder, a valve for closing the delivery port and a valve actuating rod extending into the compressor chamber when the valve is open, at a point lying in the path of the piston extension during the completion of a compression cycle of the piston and so as to be actuated thereby to close the valve.

2. In a rotary compressor having an eccentric ring piston provided with an extension forming a partition between the admission and delivery ports of the compressor cylinder, a valve for closing the delivery port, a piston and cylinder for opening the valve, a conduit leading from said cylinder to a point in the compressor chamber traversed by the piston near the end of its compression cycle, and a valve actuating rod extending into the compression chamber when the valve is open, at a point lying in the path of the piston extension during the completion of a compression cycle of the piston and so as to be actuated thereby to close the valve.

3. In a rotary compressor having an eccentric ring piston provided with an extension forming a partition between the admission

and delivery ports of the compressor cylinder, a grid slide valve for closing the delivery port, a piston and cylinder for opening the valve, a conduit leading from said cylinder to a point in the compressor chamber traversed by the piston near the end of its compression cycle and a valve actuating rod extending into the compression chamber when the valve is open at a point lying in the path of the piston extension during the completion of a compression cycle of the piston and so as to be actuated thereby to close the valve.

4. In a rotary compressor having a cylinder and slide bearing formed in its casting, a rotary eccentric ring piston provided with an extension partition and an oscillating slide to which said extension is articulated, the combination therewith of an admission port formed through the slide bearing, a valve extension of the slide operating to close said port in the interval between the operative cycles of the piston, a delivery port, a delivery valve and means for positively closing said valve actuated by the piston extension at the end of each compression cycle.

5. In a rotary compressor having a cylinder and slide bearing formed in its casing, a rotary eccentric ring piston provided with an extension partition and an oscillating slide to which said extension is articulated, the combination therewith of an admission port formed through the slide bearing, a valve extension of the slide operating to close said port in the interval between the operative cycles of the piston, a delivery port, a grid slide valve for closing said port, a cylinder and a piston for opening said valve said cylinder being connected to the compressor cylinder at a point traversed by the piston near the end of its compression cycle, and means for closing said valve lying in the path of and operated by the piston extension at the end of the compression cycle.

GUSTAV B. PETSCHE.
